(57) **CLAIM**

The ornamental design for a grille with LED daytime running lamp, as shown and described.

DESCRIPTION

FIG. 1 is a top, left and front perspective view of a grille with LED daytime running lamp, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The ghosted or low contrasted showing of the grille with LED daytime running lamp is provided for the purposes of illustrating portions that form no part of the claimed design.

1 Claim, 7 Drawing Sheets
